UNITED STATES PATENT OFFICE

CHESTER S. JENNINGS, OF SYRACUSE, NEW YORK, ASSIGNOR TO THE LAMSON COMPANY, OF SYRACUSE, NEW YORK, A CORPORATION OF MASSACHUSETTS

AUTOMATIC POWER CONTROLLER FOR PNEUMATIC-DISPATCH SYSTEMS

Application filed January 18, 1926. Serial No. 81,974.

This invention pertains to pneumatic dispatch systems of the so-called "minimum flow" vacuum type and relates more particularly to automatic power controlling apparatus for use in such a system.

Power control apparatus of this general character is disclosed in the patent to Libby No. 968,576, dated August 30, 1910. The patented apparatus provides automatic pressure actuated means for initiating a carrier propelling air flow through the transmission tube whenever a carrier is entered therein as well as means for cutting off such flow after the lapse of a predetermined period of time. While I regard the patented device as generally correct in principle and highly effective in practice I believe it preferable to have the cessation of carrier propelling air flow depend directly upon the discharge of the carrier from the delivery end of the tube rather than upon the operation of a timing device, and the principal object of this invention is to provide an improved power control apparatus comprising means actuatable automatically upon insertion of a carrier within the dispatch terminal to initiate flow of the air propelling current and also operating automatically when the last carrier emerges from the delivery terminal to cut off the air current without appreciable delay.

In the accompanying drawings I have disclosed one preferred embodiment of the invention by way of example:

Fig. 1 being a fragmentary elevation illustrating a part of the central station desk of a pneumatic system having the improved power control apparatus applied thereto;

Fig. 2 being a fragmentary vertical section to larger scale through the upper part of the suction tube showing the improved power control device applied thereto, and showing the flow controlling valve closed;

Fig. 3 is a view similar to Fig. 2 but showing the flow controlling valve wide open in the position which it occupies during the flight of the carrier;

Fig. 4 is a view similar to Fig. 2 showing the main valve just at the instant of closing and the controlling means occupying the po-

sition assumed at the discharge of the carrier from the transmission tube;

Fig. 5 is a horizontal section substantially on the line 5—5 of Fig. 2;

Fig. 6 is a vertical section substantially on the line 6—6 of Fig. 2, certain parts being omitted; and

Fig. 7 is a horizontal section substantially on the line 7—7 of Fig. 2.

Referring to the drawings, the numeral 1 indicates a fragmentary portion of the central station desk of a pneumatic dispatch system comprising transmission tubes, such for example as the tube 2 which leads from the central station to a remote sending station and then back to the central station desk. Each tube 2 is furnished with a delivery terminal 3 and is provided with a continuation 4 connecting it to an individual power control device indicated generally by the numeral 5. This power control device is connected in turn by means of a suction tube 7 to a vacuum drum or header 8^a in which a low pressure is continually maintained by means of a suitable pump, exhauster or equivalent apparatus, not shown.

An open ended dispatch terminal 6 is provided at the central station for each of the transmission tubes 2, such dispatch terminal forming the entrance to that run of the tube which leads to the corresponding remote sending station. The above arrangement in general is old and well known in this art and further details of such general arrangement are therefore unnecessary, the present invention being confined to improvements in the power control apparatus per se.

Referring particularly to Figs. 2, 3 and 4, the numeral 8 designates a substantially cylindrical and vertically disposed portion of the casing of the power control device, the part 8 being provided with a flange 9 at its lower end for the reception of the upper end of the suction tube 7. The casing of the power control device also comprises a laterally extending portion 10 having a flange 10^a adapted to receive the lower end of a tube 11 which forms a portion of the casing of the power control apparatus. The tube 11 is preferably of a diameter somewhat greater than that of

the extension 4 of the transmission tube for a purpose hereinafter to be described, and is provided with a cap 12 closing its upper end. The cap 12 is furnished with an aperture for the reception of the lower end of the tube 4.

5 The chamber 13 within the tube 11 communicates freely with the chamber 14 in the offset portion 10 of the casing and the chamber 14 likewise communicates freely with the chamber 15 in the part 8 of the casing.

10 The lower wall of the chamber 15 is defined by an annular valve seat 16, fitting snugly within the upper end of the suction tube 7, or as shown, being seated between the upper end of the tube 7 and a shoulder formed 15 upon the inner wall of the flange 9. The central opening in the valve seat 16 is of sufficient area to provide for the full flow of air necessary for propelling a carrier through 20 the transmission tube, and this central aperture in the valve seat is normally closed by the main flow-controlling valve now to be described.

25 This valve preferably comprises a main portion 17 which may be of metal or other suitable material and which is preferably provided with a washer 18 of rubber or other resilient material and which normally bears against the surface of the valve seat 16. The 30 main member 17 of the valve is furnished with one or more apertures 19 disposed eccentrically with respect to its axis and these apertures are normally closed by the secondary or pilot member of the valve. This pilot 35 member preferably comprises a disc 22 preferably furnished on its under side with a resilient washer 23 which bears against the upper face of the main member 17 of the valve.

40 The main member 17 is furnished with an opening at its center and with a guide sleeve 20 surrounding this opening and extending downwardly from its lower face. A valve actuating stem 21 passes freely through the central opening in the main member 17 of 45 the valve and through the guide sleeve 20, and the pilot member 22 of the valve is securely fixed to this stem. The stem 21 is furnished with an abutment collar 24 at a point normally spaced from the lower end of the 50 sleeve 20, the arrangement being such that when the guide stem is moved upwardly the pilot member 22 first rises and uncovers the apertures 19, and thereafter the abutment 55 24 engages the sleeve 20 and lifts the main member 17 of the valve from its seat 16.

60 The upper end of the chamber 15 is closed, preferably by means of a removable cover plate 25 and this plate supports a guide sleeve 26 through which the upper part of the valve stem 21 passes. A motor casing is mounted upon the plate 25. This motor casing comprises a lower member 27 and an upper member 28, said members being provided with engaging flanges by means of which they are 65 bolted together.

The motor casing provides upper and lower chambers 29 and 30 respectively, separated by a flexible diaphragm 31, the edge of which is clamped between the flanges of the members 27 and 28 of the casing.

70 While I have herein shown a flexible diaphragm as constituting the movable element of the motor, I contemplate that other and equivalent motor means, such for example as pistons, bellows and the like may be substituted therefor, and I may hereafter refer to this movable motive member as a pneumatic, this term being one which is familiar to those skilled in the art as comprehensive of any of the usual air actuated 75 motive devices.

75 The upper end of the valve stem 21 is preferably furnished with a radial flange 32 and is screw-threaded at 33. A weight 34 has threaded engagement with the screw-threaded portion 33 of the stem and this weight constitutes a clamping nut for securing the central part of the member 31 to the stem 21. The lower chamber 30 of the motor casing communicates freely with the external 80 air by means of an opening 35.

85 An auxiliary valve casing is mounted upon the upper part of the motor casing and this valve casing preferably comprises a substantially horizontal tubular portion 37 and a hollow foot 38 which is attached to the member 28 so that it is concentric with an opening 39 in the wall of the member 28, the end portions of the part 37 providing passages of 90 large capacity diverging from the passage in the foot 38. By the expression "passages of 95 large capacity" I desire merely to distinguish from bleeder valves or similar slow leak orifices intended to produce a timing effect, the passages here employed, when opened, 100 permitting a rapid pressure change in the chamber 29.

105 The opposite ends of the horizontal portion 37 of the auxiliary valve casing are preferably furnished with cover plates 40 and 41 respectively, and these cover plates are furnished with one or more large eccentric valve apertures or ports 42 (Fig. 6) and with 110 central guide openings. The central guide openings of the two cover plates are aligned 115 with one another and are adapted to receive and to guide the stem portion 44 of the auxiliary valve device. This valve device comprises a pair of spaced heads, the head 45 being attached to the left hand end of the stem 44 120 as shown in Fig. 2 and being provided with a resilient pad 46 adapted to cooperate with the plate 41 to close the apertures 42 therein. The other valve head 47 is likewise furnished 125 with a resilient pad or washer 48 adapted to close the openings in the other cover plate 40.

130 The left hand end of the valve casing 37 extends through an opening in the side wall of the tube 11 so that the valve head 45 is dis-

posed within the chamber 13. The stem 44 of the auxiliary valve extends beyond the head 47 and is preferably guided in an opening in a bracket 49 attached to the cover member 28 of the motor. A spring 50 is interposed between the bracket 49 and the valve head 47, and normally holds the auxiliary valve device in the position shown in Fig. 2 wherein the ports 42 in the head 41 are open and the ports in the head 40 are closed. As thus disposed, the upper chamber 29 of the motor casing communicates freely with the chamber 13 and is thus subject to pressure conditions obtaining in the transmission tube.

At a point just above the end of the auxiliary valve casing a bracket 51 is secured to the inner surface of the tube 11. This bracket provides a bearing for a transverse shaft 52 which supports an actuator vane 53. This vane is preferably of substantially circular contour and is normally disposed transversely across the chamber 13 immediately below the point at which the tube 4 enters the latter. Preferably the upper surface of this vane 53 is slightly concave and it may, if desired, be provided with a central aperture 54 to decrease its weight.

The shaft 52 extends outwardly through the side wall of the tube 11 and is furnished with a crank arm 55 carrying an adjustable weight 56 for counterbalancing the vane 53. The vane 53 is provided with a bracket 57 preferably having an adjustable contact element 58, here shown as a set screw, which is adapted as the vane swings downwardly to engage the head 45 of the auxiliary valve device and to push the latter to the right as viewed in Fig. 2 in opposition to the spring 50 thus closing the ports 42 in the cover 41 and simultaneously opening the ports in the cover 40. When the valve is thus positioned the chamber 29 of the motor is freely open to the atmosphere and is entirely cut off from the chamber 13.

In order to provide the desired minimum flow, I herein employ a tube 59 leading from the chamber 14 to the upper part of the suction tube 7, controlling the passage of air through this tube by means of a needle valve 60. While this means of providing the minimum flow is desirable, it is to be understood that other and equivalent methods of providing for minimum flow may be substituted if desired.

The operation of the device is substantially as follows: It being assumed that the parts normally occupy the position shown in Fig. 2, that a suitable flow pressure is maintained in the vacuum drum 8^a, and that the transmission tube is empty. Under these circumstances a small or minimum flow of air is constantly entering the open ended thermal tube 4 and is passing through the transmission

thereof, the chamber 13, and the tube 59, to the suction tube 7.

When a carrier is introduced into the transmission tube, either at the open terminal 6 or at the outlying station, this minimum flow is cut off or reduced in volume whereupon the increased suction in the chambers 14 and 13, acting through the open ports 42 in the valve seat 41, produces a low pressure in the chamber 49 of the motor and thus tends to raise the diaphragm 31 in opposition to the weight 34. The first effect of the upward movement of the diaphragm 31 is to raise the pilot member 22 of the controlling valve so as to uncover the apertures 19. Since these apertures are of relatively small area it is comparatively easy to lift the pilot member against the suction in the tube 7 so that the diaphragm responds sensitively to a very slight reduction in pressure. As soon as the pilot valve is open the pressures upon the upper and lower sides of the main member 17 of the controlling valve become more nearly equal and as the diaphragm continues to rise, the collar 24 engages the sleeve 20 and easily lifts the main member of the valve from its seat, thus permitting a full carrier-impelling air flow to pass through the system.

The counterweight 56 for the vane 53 is so adjusted that the vane does not tilt to any substantial extent under the action of the carrier impelling air flow entering the chamber 13 from the tube 4. The parts as thus positioned are indicated in the Fig. 3.

When the carrier is delivered from the transmission tube there is a sudden momentary increase in velocity of air through the transmission tube. This sudden rush of air is sufficient to tilt the vane 53 downwardly into the position shown in Fig. 4, and since the abutment element 58 is normally spaced from the head 45, the vane 53 may acquire considerable momentum before the member 58 strikes the head 45 of the auxiliary valve. The vane may thus strike a blow of considerable force against the head 45 which is sufficient to shift the auxiliary valve device into the position shown in Fig. 4. In this position the chamber 29 of the motor is open to the atmosphere and is cut off from the transmission tube. The pressures upon opposite sides of the diaphragm 31 are thus almost instantaneously equalized and the weight 34 causes the controlling valve to return to its seat very quickly. The equalization of pressures upon opposite sides of the diaphragm and the closure of the controlling valve takes place so quickly due to the large capacity of the auxiliary valve parts and passages that even though the vane 53 returns to its normal position immediately after its first contact with the valve head 45, the controlling valve is closed with certainty at every downward movement of the vane 53.

When the main valve is closed and the car-

rier-impelling flow cut off, the vane returns to its normal position if it has not already done so and the spring 50 immediately restores auxiliary valve device to its normal position ready for a subsequent operation.

5 While the auxiliary valve arrangement herein disclosed is desirable for the purpose, I contemplate that other and equivalent arrangements might well be employed. For 10 example, a rotary valve actuated directly or indirectly by the vane 53 might be substituted for the reciprocating valve herein disclosed, the essential being that in one position of the auxiliary valve device it shall cut off atmospheric pressure from the motor chamber 15 while permitting the latter to communicate with the transmission tube, and in its other position that it shall cut off the motor chamber from the transmission tube and permit 20 free communication between the motor chamber and the outer atmosphere.

I further contemplate that the vane 53 may be replaced by equivalent devices, for example a reciprocatory baffle plate or even by a 25 pressure operated device responsive to the change in pressure conditions in the transmission tube incident to delivery of the carrier therefrom.

While I have herein described a controlling 30 valve comprising a main portion and a pilot portion, and regard this as a desirable arrangement, it is to be understood that other types of valves may be substituted if desired since the particular form of valve employed 35 does not constitute the main feature of the present invention. It is also to be understood that the weight herein described as employed for closing the controlling valve may be replaced by the usual spring and that the shape 40 of the valve casing and associated parts may be varied as circumstances may indicate to be desirable.

I claim:

45 1. Power control apparatus for a pneumatic dispatch system of the vacuum minimum flow type having a transmission tube and an exhauster connected to the tube, said apparatus comprising a controlling valve for governing carrier impelling air flow through 50 the tube, a minimum flow of air through the tube being permitted when the controlling valve is positioned to cut off carrier impelling flow, a pneumatic for moving the controlling valve, auxiliary valve means adapted alter- 55 natively to open ports for admitting air at atmospheric pressure and at transmission tube pressure respectively to act on one side of the pneumatic, the auxiliary valve means being normally positioned to close one of said 60 ports and to uncover the other, and means for shifting said auxiliary valve means when a carrier is delivered from the transmission tube whereby to uncover the first port and to close the normally open port.

65 2. Power control apparatus for a pneu-

matic dispatch system of the vacuum mini- 70 mum flow type having a transmission tube and an exhauster connected to the tube, said apparatus comprising a controlling valve for governing carrier impelling air flow through the tube, a minimum flow of air through the tube being permitted when the controlling valve is positioned to cut off carrier impelling flow, a pneumatic for moving the controlling valve, auxiliary valve means adapted alter- 75 natively to open ports of large capacity for admitting air at atmospheric pressure and at transmission tube pressure respectively to act on one side of the pneumatic, the auxiliary valve means being normally positioned to close one of said ports and to uncover the other, and a device responsive to the rush of air through the transmission tube incident to delivery of the last carrier therefrom for shifting the auxiliary valve means to open 80 the first port and to close the normally open port.

3. Power control apparatus for a pneumatic dispatch system of the vacuum minimum flow type having a transmission tube and an exhauster connected to the tube, said apparatus comprising a controlling valve for governing carrier impelling air flow through 90 the tube, a minimum flow of air through the tube being permitted when the controlling valve is positioned to cut off carrier impelling flow, a pneumatic for opening the controlling valve to permit carrier impelling air flow through the tube, ports for admitting air at atmospheric pressure and at sub-atmospheric 95 pressure respectively to act alternatively on one side of the pneumatic, an auxiliary valve device normally occupying the same position when a carrier is in flight and when the tube is empty and when normally positioned closing one of said ports and leaving the other open, and an air actuated member responsive 100 to conditions in the tube resulting from delivery of the last carrier therefrom for momentarily shifting said valve to uncover the normally closed port and to close the normally open port.

4. Power control apparatus for a pneumatic dispatch system of the vacuum minimum flow type having a transmission tube and an exhauster connected to the tube, said apparatus comprising a controlling valve for governing carrier impelling air flow through the tube, a minimum flow of air through the tube being permitted when the controlling valve is positioned to cut off carrier impelling flow, a pneumatic for moving the controlling valve, ports for admitting air at atmospheric pressure and air substantially at suction tube pressure respectively to act alter- 115 natively on one side of the pneumatic, movable auxiliary valve means adapted to close each port, one port being closed when the other is open, and air operated means independent of 120 125 130

said pneumatic for determining the position of said auxiliary valve means.

5. Power control apparatus for a pneumatic dispatch system of the vacuum minimum flow type having a transmission tube and an exhauster connected to the tube, said apparatus comprising a controlling valve for governing carrier impelling air flow through the tube, a minimum flow of air through the tube being permitted when the controlling valve is positioned to cut off carrier impelling flow, a casing, a pneumatic constituting a movable wall for a chamber within the casing, said pneumatic being connected to the controlling valve and adapted to open the latter to permit carrier impelling air flow through the tube, ports of large capacity providing communication between said chamber and the outer atmosphere and the transmission tube respectively, a valve having elements adapted to close the respective ports, said elements being so arranged that when one closes its port the other port is open, and an air actuated device for moving said valve.

25. Power control apparatus for a pneumatic dispatch system of the vacuum minimum flow type having a transmission tube and an exhauster connected to the tube, said apparatus comprising a controlling valve for governing carrier impelling air flow through the tube, a minimum flow of air through the tube being permitted when the controlling valve is positioned to cut off carrier impelling flow, a passage for admitting air to act upon one side of the pneumatic, said passage having divergent portions leading to the atmosphere and to the transmission tube respectively, auxiliary valve means normally closing one of said divergent portions of the passage while leaving the other open, and a member responsive to the rush of air through the tube incident to the discharge of a carrier from the latter and by its response shifting said valve means to open the first divergent portion of the passage and to close the other portion thereof.

40. Power control apparatus for a pneumatic dispatch system of the vacuum minimum flow type having a transmission tube and an exhauster connected to the tube, said apparatus comprising a controlling valve for governing carrier impelling air flow through the tube, a minimum flow of air through the tube being permitted when the controlling valve is positioned to cut off carrier impelling flow, a pneumatic responsive to reduction in the minimum flow incident to insertion of a carrier in the transmission tube, means connecting the pneumatic to the controlling valve, one side of the pneumatic being normally exposed by means of a normally open passage to a predetermined air pressure, an auxiliary valve element governing said passage, a movable actuator disposed in the 55 path of the air moving through the tube and

means normally retaining said movable actuator in inactive position, said actuator responding to the sudden rush of air through the tube incident to discharge of a carrier from the latter end after a predetermined amount of movement operating to close said auxiliary valve.

5. Power control apparatus for a pneumatic dispatch system of the vacuum minimum flow type having a transmission tube and an exhauster connected to the tube, said apparatus comprising a controlling valve for governing carrier impelling air flow through the tube, a minimum flow of air through the tube being permitted when the controlling valve is positioned to cut off carrier impelling flow, an auxiliary valve device adapted alternatively to open ports for admitting air at atmospheric pressure and at transmission tube pressure respectively to act on one side of the pneumatic, the auxiliary valve device being normally positioned to close one of said ports and to uncover the other, and a movable vane for shifting said auxiliary valve device from normal position to a position in which the normally closed port is open and the normally open port is closed, said vane moving in response to abnormal velocity of air flow in the transmission tube and thereby shifting the auxiliary valve device.

9. Power control apparatus for a pneumatic dispatch system of the vacuum minimum flow type having a transmission tube and an exhauster connected to the tube, said apparatus comprising a controlling valve for governing carrier impelling air flow through the tube, a minimum flow of air through the tube being permitted when the controlling valve is positioned to cut off carrier impelling flow, an auxiliary valve device adapted alternatively to open ports for admitting air at atmospheric pressure and at transmission tube pressure respectively to act on one side of the pneumatic, the auxiliary valve device being normally positioned to close one of said ports and to uncover the other, a tilting vane exposed to the current air flowing through the transmission tube, and yieldable means for holding the vane in normal position, the vane tilting from normal position in response to abnormal velocity of air flow in the tube and thereby shifting the auxiliary valve device to open the normally closed port and to close the normally open port.

10. Power control apparatus for a pneumatic dispatch system of the vacuum minimum flow type having a transmission tube and an exhauster connected to the tube, said apparatus comprising a controlling valve for governing carrier impelling air flow through the tube, a minimum flow of air through the tube being permitted when the controlling valve is positioned to cut off carrier impelling flow, a casing, a pneumatic forming a

movable wall member for a space within the casing, said pneumatic being connected to the controlling valve and adapted to open the latter when the minimum flow is reduced by introduction of a carrier into the tube, a conduit leading to said chamber, said conduit having ports opening to the outer atmosphere and the interior of the transmission tube respectively, a movable auxiliary valve stem, means tending to hold said stem in a predetermined normal position, spaced valve heads secured to the stem, said heads cooperating with the respective ports in the conduit, one head closing its port when the other port is open, and an air operated device for moving the valve stem.

11. Power control apparatus for a pneumatic dispatch system of the vacuum minimum flow type having a transmission tube and an exhauster connected to the tube, said apparatus comprising a controlling valve for governing carrier impelling air flow through the tube, a minimum flow of air through the tube being permitted when the controlling valve is positioned to cut off carrier impelling flow, a casing, a pneumatic forming a movable wall member for a space within the casing, said pneumatic being connected to the controlling valve and adapted to open the latter when the minimum flow is reduced by introduction of a carrier into the tube, a conduit leading to said chamber, said conduit having aligned ports opening respectively into the transmission tube and the outer atmosphere, an auxiliary valve stem extending from one port to the other, valve heads secured to the stem in spaced relation such that when one valve head covers its port the other port is open, a spring tending to hold the stem in a predetermined normal position, and an air actuated vane for moving the valve stem in opposition to the spring.

12. Power control apparatus for a pneumatic dispatch system of the vacuum minimum flow type having a transmission tube and an exhauster connected to the tube, said apparatus comprising a controlling valve for governing carrier impelling air flow through the tube, a minimum flow of air through the tube being permitted when the controlling valve is positioned to cut off carrier impelling flow, a pneumatic responsive to reduction in the minimum flow incident to insertion of a carrier in the transmission tube, means connecting the pneumatic to the controlling valve, one side of the pneumatic being normally exposed by means of a normally open passage to transmission tube pressure, and means independent of the pneumatic for closing said passage and permitting the entrance of air at atmospheric pressure to act on said side of the pneumatic.

13. Power control apparatus for a pneumatic dispatch system of the vacuum minimum flow type having a transmission tube

and an exhauster connected to the tube, said apparatus comprising a controlling valve for governing carrier impelling air flow through the tube, a minimum flow of air through the tube being permitted when the controlling valve is positioned to cut off carrier impelling flow, a pneumatic responsive to reduction in the minimum flow incident to insertion of a carrier in the transmission tube, means connecting the pneumatic to the controlling valve, one side of the pneumatic being normally exposed by means of a normally open passage to transmission tube pressure, an auxiliary valve for closing said normally open passage, and means responsive to variation in rate of air flow in the tube for moving said valve to close said passage.

14. Power controlled apparatus for a pneumatic dispatch system of the vacuum minimum flow type having a transmission tube and an exhauster connected to the tube, said apparatus comprising a controlling valve for governing carrier impelling air flow through the tube, a minimum flow of air through the tube being permitted when the controlling valve is positioned to cut off carrier impelling flow, a pneumatic responsive to reduction in the minimum flow incident to insertion of a carrier in the transmission tube, means connecting the pneumatic to the controlling valve, one side of the pneumatic being normally exposed by means of a normally open passage to transmission tube pressure, an auxiliary valve element for governing said normally open passage, means tending to retain said auxiliary valve in inoperative position, and means responsive to the delivery of a carrier from the tube for imparting a sudden blow to the auxiliary valve to cause it to close said passage.

15. Power control apparatus for a pneumatic dispatch system of the vacuum minimum flow type having a transmission tube and an exhauster connected to the tube, said apparatus comprising a controlling valve for governing carrier impelling air flow through the tube, a minimum flow of air through the tube being permitted when the controlling valve is positioned to cut off carrier impelling flow, a pneumatic responsive to reduction in the minimum flow incident to insertion of a carrier in the transmission tube, means connecting the pneumatic to the controlling valve, one side of the pneumatic being normally exposed by means of a normally open passage to transmission tube pressure, an auxiliary valve for governing said normally open passage, yieldable means normally holding said auxiliary valve in open position, and means responsive to the rush of air through the tube incident to delivery of a carrier therefrom for imparting a sudden blow to said auxiliary valve to close it.

16. Power control apparatus for a pneumatic dispatch system of the vacuum mini-

5   mum flowtype having a transmission tube and an exhauster connected to the tube, said apparatus comprising a controlling valve for governing carrier impelling air flow through the tube, a minimum flow of air through the tube being permitted when the controlling valve 10 is positioned to cut off carrier impelling flow, a pneumatic responsive to reduction in the minimum flow incident to insertion of a carrier in the transmission tube, means connecting the pneumatic to the controlling valve, one side of the pneumatic being normally exposed by means of a normally open passage to transmission tube pressure, an auxiliary 15 valve element governing said passage, a pivoted vane disposed in the path of air flowing through the tube, an abutment carried by the vane adapted to engage the auxiliary valve and to move the latter to passage closing position, and means normally holding the vane 20 in inactive position with its abutment spaced from the auxiliary valve.

17. Power control apparatus for a pneumatic dispatch system of the vacuum minimum flow type having a transmission tube and an exhauster connected to the tube, said apparatus comprising a controlling valve for governing carrier impelling air flow through the tube, a minimum flow of air through the tube 25 being permitted when the controlling valve is positioned to cut off carrier impelling flow, a pneumatic responsive to reduction in the minimum flow incident to insertion of a carrier in the transmission tube, means connecting the pneumatic to the controlling valve, one side of the pneumatic being normally exposed by means of a normally open passage to transmission tube pressure, an auxiliary valve for closing said normally open passage, and an air actuated vane responsive to the rush of air through the tube incident to discharge of a carrier therefrom for moving said auxiliary valve. 30

18. Power control apparatus for a pneumatic dispatch system of the vacuum minimum flow type having a transmission tube and an exhauster connected to the tube, said apparatus comprising a controlling valve for governing carrier impelling air flow through the tube, a minimum flow of air through the tube being permitted when the controlling valve is positioned to cut off carrier impelling flow, a pneumatic responsive to reduction in the minimum flow incident to insertion of a carrier in the transmission tube, means connecting the pneumatic to the controlling valve, one side of the pneumatic being normally exposed by means of a normally open passage to transmission tube pressure, an auxiliary valve element for closing said normally open passage, a second auxiliary valve element normally closing a port for admitting air at atmospheric pressure to act on said side of the pneumatic, and a device responsive to variation in the rate of flow of air in 35

the tube for shifting said auxiliary valve elements to close said passage and to open said port.

19. Power control apparatus for a pneumatic dispatch system of the vacuum minimum flow type having a transmission tube and an exhauster connected to the tube, said apparatus comprising a controlling valve for governing carrier impelling air flow through the tube, a minimum flow of air through the tube being permitted when the controlling valve is positioned to cut off carrier impelling flow, a pneumatic responsive to reduction in the minimum flow incident to insertion of a carrier in the transmission tube, means connecting the pneumatic to the controlling valve, one side of the pneumatic being normally exposed by means of a normally open passage to transmission tube pressure, an auxiliary valve element for closing said normally open passage, a second auxiliary valve element normally closing a port for admitting air at atmospheric pressure to act on said side of the pneumatic, and a vane responsive to the sudden rush of air through the tube incident to delivery of a carrier from the tube for moving said auxiliary valve elements to close said passage and to open said port. 70
